J. T. WILLMARTH.

Bolt Machine.

No. 12,262.

Patented Jan'y 16, 1855.

Fig. 1

UNITED STATES PATENT OFFICE.

JOHN T. WILLMARSH, OF NORTHBIDGE, MASSACHUSETTS.

DIE FOR MAKING BOLTS.

Specification of Letters Patent No. 12,262, dated January 16, 1855.

To all whom it may concern:

Be it known that I, JNO. T. WILLMARSH, of Northbridge, in the county of Worcester and State of Massachusetts, have invented a new and useful Improvement in the Manufacture of Bolts, of which the following is a full, clear, and exact description, reference being had to the annexed drawings, in which—

10 Figure 1 is a section through the machine with my improvements attached. Figs. 2, 3, 4, and 5 detached views which will be hereafter referred to.

15 My improvements relate particularly to the formation of the head of the bolt, preparatory to drawing down the shank thereof. Iron bolts have been made of rods of the size of the shank of the finished bolt, the head being formed by upsetting the end of 20 the rod. Such bolts are however weakest at a point which is required to be the strongest viz the junction of the head and shank. They have also been formed of rods of the size of the head of the finished bolt or 25 slightly less, a sufficient length of the rod being first drawn down upon one side of the head to form the shank; the bolt is then cut off and the head finished in suitable dies. A great defect of this method of forming 30 the bolts is this: there being nothing but the strength of the operator to hold the bar up to the dies during the operation, it is continually worked backward, the head being constantly forced away from the dies, 35 and unless the bar is held up to the dies with exactly the same force each time, there will be a want of uniformity in the length of the bolts, rendering it necessary to put them through another operation to cut them 40 to a length. It is also found that bolts thus made are liable to have the shank out of center with respect to the head. And furthermore it is not found possible to attain an exact thickness of head by this process, 45 for the operator in judging of the length of iron to be cut off to form the head is guided only by his eye.

To remedy these defects is the object of my present invention, which consists in cutting away the iron simultaneously upon each side of the head, the iron so cut away being at the same time pressed out and partially drawn out, iron rods of the size of the finished bolt head being made use of, the 50 operation being performed by suitably formed dies which will now be described.

To enable others skilled in the art to make use of my invention I will proceed to describe its nature and the method which I have adopted of carrying it out, referring 60 generally to the machine to which my improvements are applied, and then describing the details of my invention.

65 In the accompanying drawings B is the bed piece of the machine which is firmly bolted or otherwise secured to the foundation timbers of the shop, and in which are secured the lower dies a. The upper dies are carried by the side pieces D of a vibrating frame which is constructed and operated as follows:

70 E are side posts secured at the bottom to the side pieces D, and at the top to the cap piece F; this frame is pivoted upon gudgeons G, one of which is seen in dotted lines 75 in Fig. 1 running in the boxes, H.

L are eccentrics secured to the shaft K and running in the straps or housings M. These housings are grooved so as to slide freely up and down upon the side posts E. 80 The shaft K is revolved in uprights rising from the base of the machine, its motion being regulated by the fly wheel N. As the shaft K revolves the frame D, E, F, is vibrated upon its gudgeons G so as to bring 85 the dies upon the opposite sides of the machine alternately into operation. These dies are arranged in pairs as seen in Fig. 1, their form and operation will now be described.

90 The upper and lower dies a, a', are similarly constructed and are seen in section in Fig. 2, and in elevation in Fig. 4. Fig. 3 is a plan of the lower die. y is a groove through the center of the die which divides 95 it into two portions 1 and 2 Fig. 2. Upon each side of this groove the die falls away in a curve or slant as seen in Figs. 1 and 2. At one end f' they approach each other nearer than at the other f, for a purpose 100 which will be presently made clear. In Figs. 2 and 4 these dies are seen as when nearest to each other—they are secured in place when in operation by the screws e and e'. The bed piece B has a slot R' 105 through its whole depth to permit the escape of the scale.

110 Operation: The frame which carries the upper dies being vibrated as already described a bar of square iron of the size of the head of the finished bolt or nearly so, is heated and entered between the dies a a' at

methods with which I am acquainted, among which are the following—1st, the iron being operated upon, on both sides of the head at once; the latter is not forced away from the dies as is the case when it is operated upon on one side of the head at a time, and thus a determinate quantity of iron is thrown into the shank of each bolt, and the necessity of cutting off the end of the latter to reduce the bolts to a uniform length is avoided. 2nd, the iron being gradually cut away all around the head the fibers of the metal are not distorted or ruptured, and the bolt is much stronger at this point than can be the case where other methods of working the iron are adopted. 3d, the shank is never out of center with respect to the head as is often the case with bolts formed by other methods.

What I claim as my invention and desire to secure by Letters Patent is—

The dies a, a' constructed as described, or

The dies *a a* constructed as described, or in any manner substantially equivalent thereto, for the purpose of operating simultaneously upon both sides of the head as set forth. 55

JOHN T. WILLMARTH.
